UNITED STATES PATENT OFFICE

GUSTAV J. R. THAMM, OF NEW YORK, N. Y.

VACUUM CLEANER ATTACHMENT

Application filed October 24, 1928. Serial No. 314,727.

The invention relates to attachments to be removably fitted to the flexible tube of vacuum cleaning machinery, and provides a brush tipped nozzle designed most especially for tufted upholstery to enable the creases, folds and depressions to be reached.

The nozzle is formed with a flattened end and curved tip in which is provided the opening through which the dust laden air is drawn when the device is in action. Plates are adapted to be interchangeably fitted to the flattened sides of the nozzle and are provided with brush material. The outer marginal edges of the plates are preferably channeled for strength and reception of the bristles or other material forming the brush.

The invention will be described more fully hereinafter, and corresponding parts are referred to in the specification and designated in the several views of the accompanying drawings by like reference characters.

In the drawings:

Figure 1 is a side view of a vacuum cleaner nozzle embodying the invention a portion being broken away.

Figure 2 is a detail sectional view on the line 2—2 of Figure 1 looking in the direction indicated by the arrows.

Figure 3 is a transverse sectional view on the line 3—3 of Figure 2.

The numeral 1 denotes the nozzle and 2 the usual flexible tube of a vacuum cleaner. In accordance with the present invention the extremity of the suction end of the nozzle is curved and formed with an opening 3. The receiving end of the nozzle is flat. A plate 4 is fitted against each side of the flattened end and is coextensive therewith.

Screws 5 or like fastening means secure the plates 4 to the sides of the flattened end of the nozzle. It is observed that the plates 4 may be fitted to either side since one is the counterpart of the other. The outer marginal portion of each of the plates 4 is pressed outwardly, as indicated at 6, to form a channel which reinforces the plates and provides convenient means for the attachment of brush material 7 to the plates.

The brush material 7 may consist of bristles which may be attached to the plates in

any manner practiced in the art. The arrangement results in the provision of a brush which projects beyond the sides and edges of the flattened end and worn brushes may be readily replaced at a nominal cost. The attachment is designed chiefly for upholstered furniture, as it enables the creases, folds and crevices to be easily reached for removal of the dust, lint and other accumulation.

Having thus described the invention, I claim:

A vacuum cleaner nozzle having flattened sides providing a flattened end portion, said sides being rounded at their ends and spaced apart to provide a suction opening, plates of the same shape as the sides removably attached thereto, said plates having channeled projections extending adjacent the sides of said nozzle, and brush bristles attached to the outer side of said channeled projections.

In testimony whereof I affix my signature.
GUSTAV J. R. THAMM. [L. S.]
